US0D1069342S

(12) **United States Design Patent** (10) **Patent No.:** **US D1,069,342 S**
(45) **Date of Patent:** **** Apr. 8, 2025**

(54) **SLIDE SLIPPER**

(71) Applicant: **Fuzhou Rongzhong Max Supply Chain Management Co., LTD.,**
Fuzhou (CN)

(72) Inventor: **Jiansong He**, Fuqing (CN)

(73) Assignee: **Fuzhou Rongzhong Max Supply Chain Management Co., Ltd.,** Fuzhou (CN)

(**) Term: **15 Years**

(21) Appl. No.: **29/843,684**

(22) Filed: **Jun. 23, 2022**

(30) **Foreign Application Priority Data**

May 13, 2022 (CN) 202230281324.2

(57) **CLAIM**

The ornamental design for a slide slipper, as shown and described.

DESCRIPTION

FIG. 1 is a front, bottom and left side perspective view of a slide slipper, showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines in the drawings illustrate the portions of the slide slipper, which form no part of the claimed design.

1 Claim, 7 Drawing Sheets
